UNITED STATES PATENT OFFICE.

WILLIAM H. SHEASBY, OF LOS ANGELES, CALIFORNIA, ASSIGNOR TO ANTI-FRICTION JOURNAL BOX COMPANY, OF LOS ANGELES, CALIFORNIA, A CORPORATION OF CALIFORNIA.

JOURNAL-BOX.

No. 849,274.

Specification of Letters Patent.

Patented April 2, 1907.

Application filed December 17, 1906. Serial No. 848,353.

To all whom it may concern:

Be it known that I, WILLIAM H. SHEASBY, a citizen of the United States of America, and a resident of Los Angeles, in the county of Los Angeles and State of California, have invented certain new and useful Improvements in Journal-Boxes, of which the following is a full and clear specification, reference being had to the accompanying drawings, in 10 which—

Figure 1 is a vertical section taken longitudinally through the box; Fig. 2, partly an end elevation and partly a vertical transverse section on the line 2 2 of Fig. 1, and 15 Fig. 3 a perspective view of the closure-plug detached.

The object of this invention is to adapt the journal-box for use more particularly with a journal of the type wherein is employed a circular series of antifriction load-sustaining rollers; and its especial object is to provide a simple, strong, and efficient closure plug or cap for the outer end of the box.

Referring to the drawings by reference 25 characters, A designates the journal of a car-axle of the usual construction having keyed to it by a key *w* a bearing-sleeve B, this sleeve being provided at each end of its bearing-surface with a radial track-flange *b*, on which is 30 adapted to run an annular series of spacing-rollers F, whose ends are grooved at *f*, where the rollers engage the tracks and are held in place on the tracks by the loose rings G. Intermediate these spacing-rollers are the load-sustaining rollers E, which support the cylindrical outer member or box D. I make no claim to the foregoing construction, as it is 35 shown and described in the patent granted to Green, Lyons, and Garey, numbered 40 802,362, dated October 17, 1905.

Longitudinal grooves *a* are formed in the axle-spindle near the outer end thereof at diametrically opposite points, and registering holes *b'* are formed in the sleeve B, whereby 45 a suitable tool may be inserted in said grooves *a* and engaged into holes *b'* for the purpose of drawing the sleeve off the spindle when it becomes worn. The grooves *a* are 50 covered by the sleeves except where the holes *b'* register with the grooves at the inner ends

of the grooves. The ends of the grooves *a* are covered by a ring-plate C, removably secured to the end of the spindle by means of lag-bolts *c*. This ring C overlaps the end of the sleeve B and serves to assist in holding it 55 on the spindle.

A pin or plug *a'* is driven into a tapered hole formed in the center of the end of the axle. The head of this pin transmits the end thrust of the axle to a freely-rotatable ball I, 60 confined in a central recess *h*³ in the cylindrical plug II of the journal-box. This ball is loosely confined in said recess by a ring-like plate J, secured to the inner face of the plug, and the ball at a point opposite its bearing-point on the plug *a'* bears against a wear-plate K, set in a recess in the bottom of the recess *h*³. In this manner the ball is loosely retained in the cap and is free to rotate in all directions, whereby the end thrust of the axle 70 will be taken up with the least possible friction and wear. A central axial passage *h*⁴ is formed in the cap to permit the insertion of a suitable tool for the removal of the wear-plate K when it is necessary to renew the 75 same.

In a rabbet or annular recess *d*⁴, formed in the inner end of the journal-box, is fitted a suitable ring of flexible packing L, which is held against rotation by means of pins *d*³, 80 fastened in the end of the box and projecting partly into the packing-ring. This packing-ring bears upon the face of the spindle and prevents the entrance of dust to the box, and it is held in place by an annular ring m, whose 85 peripheral edge engages over an annular flange on the exterior of the box. The closure plug or cap II is formed cylindrical in shape and is of a diameter to nicely fit within the outwardly-projecting end of the box. 90 The inner end of this cylinder is closed by a head, from the center of which a boss outwardly projects to provide the metal necessary for the ball-retaining recess *h*³, and the outer end of this boss is shaped into a nut *h*², 95 whose outer surface is flush with the end of the box and which is adapted to receive a wrench for the removal of the plug from the box. The plug is held in the end of the box by means of two series of radial peripheral 100

flanges h' , formed on the surface of the plug at diametrically opposite sides of the same, each flange extending quarter-way around the periphery of the plug. These segmental flanges are adapted to interlock with a series of similarly shaped and disposed flanges d , formed on the interior of the box.

To insert the plug, it is simply necessary to adjust it axially, so that its flanges h' shall come opposite the diametrically opposite spaces between the box-flanges d , then insert the plug into the box, and then give it a quarter-turn in order to interlock the flanges h' with the flanges d , as shown in Fig. 1. To lock the plug in its closed position, I tap through the box a set-screw d^2 , which engages the outer face of one of the flanges h' . An annular flange d' is formed on the interior wall of the box in such position that the inner end of the closure-plug will abut against it when the plug is slid in to a point where its flanges will engage the lock-flanges on the box. An annular radial flange h is formed on the outer end of the plug and is adapted to fit within and be flush with the outer end of the box when the plug is inserted and locked, this flange serving, therefore, to cover the ends of the recesses or spaces between the ends of the segmental lock-flanges.

30 The above-described closure-plug is simple in construction, easy to insert and to remove, effectually excludes all dust when closed, and affords a rigid support for the end-thrust ball I .

35 Upon the upper surface of the box is formed a hemispherical boss N , which is adapted to receive the bearing-block O of the truck-frame, the under side of this block being provided with a hemispherical socket 40 which nicely fits and freely works upon the boss N . The object of this construction is to afford a universal pivotal connection between each journal-box and the truck-frame, whereby the twisting and distorting of the truck-frame will not be communicated to the box, it being obvious that if the distortions and twisting of the truck-frame were communicated to the box the bearing-rollers would be subjected to unequal strains. This construction is especially advantageous where, as in the present case, the bearing-rollers are comparatively long, extending, as they do, the full length of the bearing portions of the axle structure and the box.

55 Having thus fully described my invention,

what I claim, and desire to secure by Letters Patent, is—

1. In combination with an axle structure and a journal-box inclosing the same and having a projecting cylindrical end portion, 60 there being an annular interior stop-flange d' in this projecting portion of the box, and a series of inwardly-projecting separated segmental flanges on the interior of this projecting portion between said stop-flange and the 65 outer end of the box, and a closure-plug cylindrical in shape and provided with a series of separated segmental outwardly-extending flanges on its outer surface and an annular radial flange h on its outer end adapted to fit 70 within the outer end of the box, and a locking device for this closure-plug.

2. In combination with an axle structure and a cylindrical box inclosing the same, a closure-plug in the outer end of this box provided with a central recess h^3 , a ball confined in this recess, a wear-plate K at the bottom of this recess to receive the end thrust of the ball, said closure-plug being provided with a passage h^4 leading from the outer face of the 80 plug to said wear-plate K .

3. In combination with a journal-box having formed in its outer end a series of inwardly-projecting separated segmental flanges, a closure-plug cylindrical in shape 85 adapted to fit within the end of the box and provided with two series of outwardly-projecting separated radial flanges adapted to fit between and interlock with the flanges on the box, and a locking device for this plug. 90

4. In combination with a journal-box having formed in its outer end opposite inwardly-projecting segmental flanges and an inwardly-projecting flange inside of said flanges, a closure-plug carrying an end-thrust element in 95 its inner end or face and provided peripherally with outwardly-projecting segmental flanges, said plug being adapted to fit within the outer end of the journal-box, a locking device for the plug, and an axle having its 100 spindle portion journaled in the box and its outer end engaging said end-thrust element.

In testimony whereof I hereunto affix my signature, in the presence of two witnesses, this 14th day of December, 1906.

WILLIAM H. SHEASBY.
